UNITED STATES PATENT OFFICE.

HENRY W. BISCHOFF, OF CHAPPAQUA, NEW YORK.

DESIGN FOR A CLOCK-CASE.

SPECIFICATION forming part of Design No. 21,182, dated November 24, 1891.

Application filed October 17, 1891. Serial No. 409,080. Term of patent 7 years.

To all whom it may concern:

Be it known that I, HENRY W. BISCHOFF, a citizen of the United States, residing at Chappaqua, in the county of Westchester and State of New York, have invented and produced a new and original Design for a Clock-Case, of which the following is a specification, reference being had to the accompanying drawing, forming a part thereof, which represents a perspective view of a case embodying the features of my design.

The leading feature of the design consists

in a figure simulating in general contour a lady's boot and ornamented by a fanciful figure simulating a time-dial. As an adjunctive feature the leading or body figure appears as mounted upon a base.

I claim—

The design for a clock-case, substantially as herein shown and described.

HENRY W. BISCHOFF.
